Poly Vinyl Creations Fence Manufacturer re Tru Close Regular—
Standard for gates up to 66 lbs/ 30 kg; <http://www.polyvinylc.com/DanDTecholgoeisDetails.php?ID=17>[Nov. 7, 2013 5:33:35 PM].*Primary Examiner* — Cynthia Underwood(74) *Attorney, Agent, or Firm* — Luedeka Neely Group, PC(57) **CLAIM**

The ornamental design for a hinge cover, as shown and described.

DESCRIPTION

FIG. 1 is a front perspective view of a hinge cover shown reduced in scale for ease of illustration and mounted onto a fence post and gate;

FIG. 2 is a front perspective view of the hinge cover of FIG. 1;

FIG. 3 is another front perspective view of the hinge cover of FIG. 1;

FIG. 4 is a front plan view of the hinge cover of FIG. 1;

FIG. 5 is a rear plan view of the hinge cover of FIG. 1;

FIG. 6 is a top plan view of the hinge cover of FIG. 1;

FIG. 7 is a bottom plan view of the hinge cover of FIG. 1

FIG. 8 is a left end view of the hinge cover of FIG. 1; and,

FIG. 9 is a right end view of the hinge cover of FIG. 1.

The broken lines in the drawings are included for the purpose of illustrating unclaimed features and form no part of the claimed design.
